UNITED STATES PATENT OFFICE.

HERBERT J. LONG, OF NEW BRUNSWICK, NEW JERSEY, ASSIGNOR TO THE LONG-LANDRETH-SCHNEIDER COMPANY, OF NEW BRUNSWICK, NEW JERSEY.

EMERGENCY FUEL-VALVE CONTROL.

1,325,896.

Specification of Letters Patent.

Patented Dec. 23, 1919.

Application filed October 11, 1916. Serial No. 125,117.

To all whom it may concern:

Be it known that I, HERBERT J. LONG, a citizen of the United States, residing at 239 Harrison Ave., New Brunswick, in the 5 State of New Jersey and county of Middlesex, have invented a new and useful Improvement in Emergency Fuel-Valve Controls, of which the following is a specification, the principle of the invention being 10 herein explained and the best mode in which I have contemplated applying that principle, so as to distinguish it from other inventions.

My invention relates to a safety provision 15 or auxiliary thermostatic control for water heaters and more particularly to the adaptation of a fusible plug in a by-pass connection so that the water pressure established therein on emergency, insures the closing 20 of the fuel valve.

I am well aware that fusible plugs composed of an alloy of predetermined melting temperature have been long employed in many arts not excepting that of water heaters. 25 Of this United States Patents numbered 660,358, 779,711, 1,082,181 and 1,166,531 issued in 1900, 1905, 1913 and 1916 to Bullard, Hoffman, Meacham and Lovekin respectively, bear witness.

The object of my invention is to so improve upon earlier expedients as to achieve 30 the desired insurance against the waste and damage which is due to overheating, in a more simple, direct and certain manner. It 35 should be understood that this provision of a safety control for fuel valves, ordinarily operated by a thermostat and power translating mechanism connected therewith, is desirable rather than necessary, and hence recommended as an auxiliary actuation for closing 40 the fuel valve only because of the chance of a defective commercial construction, as for example a leak in the tube containing the expansion fluid or a bind in the mechanism. 45 In other words, the need of my present invention in conjunction with a thermostat is due solely to circumstances beyond human control.

With the foregoing and other objects in 50 view the invention consists of the novel construction, combination and arrangement of parts as hereinafter more specifically described and illustrated in the accompanying

drawings, wherein is shown an embodiment of the invention, but it is to be understood 55 that changes, variations and modifications can be resorted to which come within the scope of the claims hereunto appended.

Figure I is an elevation of a storage water heater system showing my present invention 60 in connection therewith.

Fig. II is an enlarged section of the construction constituting the subject matter of this invention.

Fig. III is a view corresponding to Fig. 65 II showing a modification.

In Fig. I is seen a suitable pedestal 1 which supports a heater 2 with a suitable gas connection 3, storage tank 4 and thermostatically operated mechanism there designated in its entirety by the numeral 5, which is, however, a closed and necessarily air tight housing casting with which all the other parts pertaining to this invention are either directly or indirectly connected. 70 Directing attention henceforth to Fig. II it will be noticed that the casting 5 is provided with five screw threaded openings, namely, a gas inlet 6, a gas outlet 7, an adjustment opening 8 and openings 9 and 10 75 for the entrance of a thermostatically actuated member and a valve stem respectively.

The gas inlet 6 is, of course, intended to be suitably connected with a source of fuel supply not shown, whereas the gas outlet 7 is 80 to be connected or disconnected from the connection 3 leading to the heater through the agency of a suitable valve to be now described. Seated in the opening 7 is a male union 11 having its inner end formed as a valve seat 12 and its outer end provided with a washer 13 held between it and a tail piece 14 by means of a nut 15. Interiorly of the union 11 is a concentric guide 16 adapted to control the movement of the guide stem 95 17 of a valve 18 adapted to coöperate with the seat 12 in the usual way and provided on the opposite side with an actuating valve stem 19.

Seated in the opening 9 is another union 100 20 which is designed to carry the thermostatic element which in this instance is a tube 21, to be filled with a suitable expandible fluid such as ether and to be positioned within the storage tank 4 as appears in Fig. 105 I. The tube 21 is shown seated in a suitable

depression and held therein by a plug 22 having a central opening 23. Through this opening a thrust rod 24 extends in one direction into the tube 21 and in the other direction through the union 20 into the housing 5. The rod 24 is surrounded by any approved type of bellows 25 which by reason of being secured to the upper end thereof is adapted to move the rod in and out according to the expansion and contraction of the ether. Thus the rod 24 may be considered as a prime mover. That end of the rod 24 which is located interiorly of the housing 5 carries a thrust member 26 provided on its extremity with a knife edge 27, adapted to bear against a complementary surface upon a lever which constitutes one part of the toggle mechanism for effecting a snap action as shown, described and claimed 20 in my Patent No. 1,231,527 issued June 26, 1917. The description of such exemplifying snap mechanism will be undertaken later. The member 26 is hollow and extending into it is an adjusting screw 28 which carries a pin 29 adapted to be quite loosely engaged by an inclosing adjusting screw 30 which is in turn screw threaded into the opening 8 so as to be accessible to exterior manipulation. The outer extremity of the adjusting screw 30 is shown covered with a suitable cap 31. The thermostatic mechanism just now described is purposed to permit of an adjustment whereby the throw of the thrust rod 24 may be regulated within predetermined limits of temperature.

The lever 32 which is to be engaged and moved by the knife edge 27 is pivoted upon a pin 33 secured to a stud 34 a suitable distance from the walls of the housing 5. Movement of the lever 32 by the thrust of the rod 24 is resisted by a suitable spring 35. The lever 32 has its own extremity likewise provided with a knife edge 36. Another lever 37 is also pivoted upon the pin 33 and extends beyond the knife edged extremity 36 where its extremity articulates at 38 with the actuating valve stem 19. Near its point of articulation the lever 37 is also provided with a knife edge 39. Interposed between the knife edges 36 and 39 is a reacting structure composed of male and female guides 40 and 41 respectively and both surrounded by a balance spring 42. In this manner, as the lever 32 passes its neutral position, and its knife edge 36 as well as the knife edge 39 on the lever 37, come in line with the pivot 33, it will be caused suddenly to snap to one side thereof or the other and in so doing cause the lever 37 likewise to snap but in 60 the opposite direction whereby to suddenly either open or close the fuel valve.

The male spud of the separable union 20 is itself provided with a lateral opening 43 in which a spud 44 is secured. That end of the bore of the spud 44, which communi-

cates more directly with the union 20 is provided with a fusible plug 45 adapted to melt when subjected to a temperature by the water in the tank 4 such as may be determined upon. Of course, the melting temperature of the plug 45 will be fixed at a degree higher than the temperature ordinarily required to actuate the toggle mechanism for the closing of the fuel valve 18. The other end of the spud 44 is connected by 70 means of a nut 46 with a copper tube 47 having communication with a safety chamber composed of two parts 48 and 49 between which a diaphragm 50 is secured. The component part 49 is suitably fitted into 80 the opening 10 of the housing 5. Fixed to the diaphragm 50 is a safety stem 51 axially aligned with and adapted to impinge against the free extremity of the actuating valve stem 19 when the diaphragm 50 is moved by 85 the incoming water pressure. On the opposite side a spring 52 is operatively positioned so as to normally hold the diaphragm 50 and hence the safety stem 51 in a normal position beyond the range of movement of the 90 actuating valve stem 19.

In operation the snap actuation of the fuel valve 18 to either open or closed position, in response to the influence of varying temperature upon the thermostatic mechanism, in the ordinary course has an alternating action giving the desired results so long as the mechanism is operating satisfactorily. In the event that conditions arise which either delay or preclude the timely control 100 of the valve due to the changes of temperature within certain prescribed limits, the safety expedient of my present improvement is called into action. Manifestly, in the event of such a happening the valve may 105 too long remain open with a consequent overheating of the water, enough presently to fuse the plug 45 and effect the application of pressure to the near side of the diaphragm 50 which is thereby flexed to move 110 the stem 51 and as adjusted the stem 19 also sufficiently to firmly seat the valve 18. It should moreover be understood that the actuation of my safety control is truly auxiliary in that it actuates the same fuel valve 115 and in the same manner that it would be otherwise actuated had the unavoidable conditions not occurred to hinder the operation of the snap mechanism.

The modified form of my invention in 120 Fig. III, on Sheet 2 of the drawings, involves an alteration in the relative locations of certain parts and as a consequence a change in minor respects as to the shape of specific details. Principally the difference consists 125 in presenting the thermostatic tube, which is intended to be inserted in the storage tank, at an angle of 90 degrees to the valve stem instead of parallel thereto and in also reversing the relation of the valve to its 130

seat and hence the location of the diaphragm, whose flexing is communicated to the safety valve stem for action against the opposite extremity of the normally actuating valve stem. Such an arrangement permits of the construction as a whole to be better fitted and to be better accommodated in space made available by a popular type of water heater now on the market. A housing 53 carries interiorly the snap toggle mechanism which connects the thrust rod 54 with the actuating valve stem. It will be noticed that a bell crank lever 55 has been substituted for the lever 32 in order to be similarly actuated by a knife edge connection with the extremity of the thrust rod 54. The spud which supports the thermostatic tube has a tube 56 leading from it to the diaphragm 57, so that when the latter is flexed its movement is transmitted to the safety stem 58 and thence to the valve 59 to be ordinarily operated by the actuating stem 60.

I claim:

1. A device of the character described comprising a fuel valve, a stem connected therewith, mechanism constantly connected with said stem and adapted to actuate the same in opposite directions, thermostatic means for actuating said mechanism and a safety thermostatic appliance adapted to operate at a predetermined temperature and to move into engagement with said stem to close said valve.

2. A device of the character described comprising a valve, a thermostat, mechanism connected to said valve and normally adapted to hold said valve open, said thermostat being adapted to close said valve, and a safety thermostatic appliance adapted to control the movement of said mechanism to close said valve, said appliance including a member adapted to engage a part of said mechanism.

3. A device of the character described comprising in combination, a water heater, a burner, a fuel valve for said burner, a valve actuating stem, a storage tank, thermostatic mechanism operatively connected with said valve stem, and a safety thermostatic appliance including a fusible element exposed to the temperature of the water, a motor, another safety stem axially aligned with the first, said safety stem being operated by said motor which is in turn operated by the water pressure which is allowed to act when said element fuses whereby said appliance is controlled by the pressure of the water for operating said valve and for controlling said mechanism.

4. A device of the character described comprising in combination, a water heater, a burner, a fuel valve therefor, a storage tank, mechanism for opening and closing said valve, a thermostat for actuating said

mechanism, a safety appliance also adapted to actuate said mechanism and including a motor forming a part of a hollow connection with said tank, and a fusible plug in such connection whereby the action of said motor is determined by a predetermined temperature.

5. A device of the character described comprising a valve actuating member, and a pair of thermostatically operated devices adapted successively to exert a force tending to move said member in the same direction.

6. A device of the character described comprising a valve, thermostatic prime mover element, snap mechanism connected therewith for suddenly either opening or closing said valve, another thermostatically controlled mechanism operable in response to a relatively higher temperature and adapted to control said first mentioned mechanism and close said valve only when said first mentioned mechanism has failed to close said valve.

7. A device of the character described comprising a valve, a valve actuating member, a thermostatic prime mover, mechanism for moving said member so as to both open and close said valve, said mechanism being adapted for transmitting movement of the latter to the former and including; an arm connected with said member and a device operatively connecting said prime mover and arm; and a safety appliance operable in response to the existence of a predetermined temperature and including a part adapted to move said member to its valve closing position whenever said prime mover fails to transmit movement to said mechanism for such purpose.

8. A device of the character described comprising a valve actuating member, a thermostatic prime mover, an arm articulating with said member, mechanism adapted to be operated by said prime mover and to actuate said arm whereby to shift the position of said member, and a safety appliance adapted to control the position of said member and including a fluid pressure motor.

9. A device of the character described comprising a water heating conduit, a burner, a fuel valve, a thermostatic prime mover immersed in the conduit water, means connected with said prime mover for actuating said valve, and a safety control mechanism including: a pressure motor, a duct having one end closed by said motor and adapted to have operative communication with the water circulating system, and a plug obstructing such communication and fusible at a predetermined temperature, said motor being arranged to close said valve when such communication is established.

10. A device of the character described

- comprising a valve, a thermostatic prime mover, means operatively connecting said elements and adapted positively to transfer reverse movements of the latter to the former, a motor appliance acting upon and adapted to absolutely control the position of the same valve, the operation of said appliance being likewise subject to thermostatic action at a temperature sufficiently high to be inutile unless said prime mover proves inoperative. 5
11. A device of the character described comprising a valve actuating member, and a pair of thermostatically operated devices adapted successively and at distinct temperatures to exert a force tending to move said member in the same direction, one such device being dependent upon the factor of expansion and the other upon pressure. 15
12. A device of the character described comprising a water heating conduit, a burner, a fuel valve for said burner, a thermostatic prime mover, means operatively connecting said valve and prime mover, and a safety appliance including; a tube in connection with said water heating conduit, a motor at one end of said tube, a fusible plug near the other end of said tube and exposed to the temperature of the water in said conduit, and means connected with said motor and adapted to close said valve, said valve being movable independently of said motor controlled actuating means. 25
13. A device of the character described comprising a support, a prime mover carried thereby, a valve stem movably mounted upon said support, means operatively connecting said prime mover and stem, and an emergency motor appliance adapted to move said stem and when functioning to overcome the control of the latter by said prime mover, said appliance being so adjusted as to be normally inactive and adapted to functionate only when said prime mover fails to operate. 30
14. A device of the character described comprising a closed housing provided with fuel inlet and outlet openings, a valve at one of said openings, a thermostatic prime mover entering and constantly in air tight connection with said housing, a distinct thermostatically controlled and pressure actuated motor appliance having a part movable in said housing, mechanism within said housing for normally operating said valve to open position, said mechanism being successively subject to actuation both by said prime mover and motor part whereby to operate said valve to closed position at either of two predetermined temperature stages. 50
15. A device of the character described comprising a closed housing provided with fuel inlet and outlet openings, a valve at one of said openings, a thermostatic prime mover entering said housing and having a threaded bore, a complementarily threaded member adjustably fitted in said bore, an adjusting screw threaded in said housing for turning said member, mechanism operatively connecting said prime mover and valve and adapted to have its range of movement prescribed by said adjustment, and a distinct normally inactive motor appliance adapted to control the position of said mechanism to close said valve. 70
16. Apparatus for heating and causing the circulation of water comprising the combination of a heating conduit, a gas burner, a gas valve, a storage tank connected with said conduit, a thermostat operatively associated with the circulating system, mechanism connecting said thermostat and valve and including a spring normally acting to hold said valve open, said thermostat adapted to close said valve whenever the water in said system reaches a predetermined temperature, and an emergency control device for closing said valve and including; a separate water passage, a plug fusible at a predetermined temperature and normally closing said passage off from said circulatory system so as to be unexposed to the water therein, a movable member adapted to be actuated by the water pressure established in said passage whenever said plug has melted and when so actuated to engage a part of said mechanism, overcome its spring and close said valve, and a spring normally acting to hold said member beyond the range 90 of movement of said mechanism part. 95
17. A device of the character described, comprising a fuel valve, mechanism operatively connected with said valve and adapted to actuate it to either its open or closed position, a thermostat connected with said mechanism and adapted to move the same, and an emergency control device adapted to absolutely control the position of said valve. 105
18. A device of the character described comprising a fuel valve, mechanism operatively connected with said valve and adapted to actuate it to either its open or closed position, a thermostat connected with said mechanism and adapted to move it in one direction, a spring adapted to move said mechanism in the opposite direction and an emergency control device adapted to overcome said spring and close said valve. 110
19. A device of the character described comprising the combination with a hot circulating water heating system including a heater, a burner and a storage tank, of a fuel valve for said burner, mechanism operatively connected with said valve and adapted to actuate it to either its open or closed position, a thermostat operatively connected with said mechanism and adapted to move it in one direction to close said valve, a spring adapted to move said mecha- 125
- 130

nism in another direction to open said valve, and an emergency control device including a distinct valve operating part, a plug fusible at a predetermined temperature and a conduit normally closed by said plug for leading water under pressure against said part whenever said plug melts.

Signed by me, this 4th day of October, 1916.

HERBERT J. LONG.
